TANK CAP

Frank N. Mariani, Washington Heights,
New York, N. Y.

Application August 26, 1949, Serial No. 112,560

7 Claims. (Cl. 220—86)

1

This invention is a tank cap particularly applicable to a liquid conducting conduit extending from a fluid receiving tank carried by self propelled machines. The object of the invention resides in the provision of a simplified but improved tank cap wherein the shell thereof is appreciably interrupted by a relief opening to completely receive the swingable self closing closure of the cap adapted to be actuated by a fluid conducting nozzle when inserted into the cap whereby the closure fully clears the bore of the shell to preclude interference with the fuel in its passage to the fluid receiving or gas tank, thereby permitting the latter to be filled more quickly. Another object deals with novel means to provide a seal tight connection between the conduit or cap retainer and the tank cap. Other important objects, features, and functional and structural advantages of the invention will appear from the following detailed description taken with the accompanying drawings wherein:

Fig. 1 is a perspective view of the tank cap according to my invention shown closed and mounted on a fluid conducting conduit extending from the gas tank.

Fig. 2 is an enlarged vertical sectional view of the tank cap shown in Fig. 1 but rendered inaccessible by a swingable door carried by one of the rear fenders.

Fig. 3 is a transverse sectional view on the line 3—3 of Fig. 2.

Fig. 4 is a fragmentary perspective view of the upper part of the gasoline conduit or pipe however with the tank cap removed therefrom.

Fig. 5 is a fragmentary view of Fig. 2, illustrating the swingable closure carried by the tank cap fully depressed and clear of the bore of vertically slotted tubular grill or shell.

Fig. 6 is a sectional view on the line 6—6 of Fig. 5.

Fig. 7 is a sectional and fragmentary view of the tank cap showing the head detached from the shell.

Fig. 8 is an underneath view of the head of the tank cap taken on the line 8—8 of Fig. 7.

Fig. 9 is a view taken on the line 9—9 of Fig. 7 however showing the swingable cover opened and

Fig. 10 is a perspective view of the head and shell detached but with the closing closure.

The tank cap broadly denoted TC is characterized by a relatively large annular head H having secured thereto cylindrical shell or tube S which includes at its bottom the spaced bars B defining a grill to preclude undesirable large objects from flowing into tank T. For a similar

purpose the cylindrical body of the shell is also in the form of a grill being interrupted by the spaced vertically arranged slots 10 to constitute spaced bars or baffles 11.

Head H embodies the downwardly expanding tapered opening or orifice 12 normally held shut by the frusto conical closure 13 merged with arm 14 having spaced depending ears 15 interposed between spaced lugs or ears 16 integral with and extending from the upper part of the tube or shell S. Fulcrum pin 17 extends through the ears 15 and lugs 16 to pivotally sustain closure 13 relative to shell S and head H.

As previously mentioned closure 13 normally seals orifice or opening 12 in head H. In other words the pivoted closure is automatically held fully elevated. This is accomplished by the spring 18 coiled about fulcrum pin 17 and having one free and relatively long offset end 19 retained within the slot 20 of projection 21 extending from the inner face of closure 13. This end 19 is also confined in groove 22 interrupting the lower face of arm 14. The other free end 23 of spring 18 is retained within groove 24 in the underface of head H. By the present arrangement, the spring 18 is wound up when closure 13 is depressed as in the case of insertion of a liquid ejecting nozzle (not shown) in orifice 12. However to preclude interference on the part of the closure 13 at this time, it will be observed that the slotted shell S is interrupted by a relatively deep relief opening 25 at the upper part thereof. Thus with the fluid ejecting nozzle inserted within orifice 12, this nozzle will pivotally displace closure 13 downwardly and fully into and out of relief opening 25 and even beyond shell S into the annular channel 26 defined by the tubular retainer or conduit 27 extending from and in communication with fuel holding tank T. Conduit 27 is provided

at its upper end with the inwardly overhanging rim 28 interrupted by diametrically arranged slots 29. Conduit 27 is spaced from and extends underneath the swingable panel or door D on one of the rear fenders F.

Ordinarily pivoted door D renders the tank cap TC inaccessible (Fig. 2) but when raised, the fluid ejecting nozzle is adapted to operate and fully depress the spring actuated pivoted closure 13 into relief opening 25, thereby the entire cross sectional area or bore of the cylindrical shell is rendered free and utilized, thus facilitating prompt filling of the tank and without interference as previously stated from the self closing closure 13 which is now maintained out of the

way by the nozzle in the annular compartment or channel 26.

In mounting tank cap TC on conduit 27, door D is swung open or raised, shell 13 is inserted into conduit or pipe 27 so that diametrically arranged keys or lugs 31 projecting from shell S enter slots 29. Thereafter the shell is dropped whereby the tapered and downwardly contracted neck N falls against the inner margins or seats L of the interrupted annular and inwardly overhanging rim 28 which may be considered as a retainer for the tank cap. It will be observed that a resilient washer W is within annular flange 30 of head H and is seated on the annular rim 28. The washer is compressible and insures a seal tight connection when cap TC is rotated relative to the retainer or conduit 27. Anchored in slots 32 in diametrically arranged keys 31 are the primary and secondary leaf springs 33 and 34, both of which extend at an angle and upwardly beyond the respective lugs, the springs 33 extending beyond the springs 34. The ends of springs 33 cooperate to hold washer W tightly on seat or rim 28 after keys 31 which extend laterally of shell S strike stop lugs 35 depending from lips L. Springs 34 strengthen the action of springs 33 to maintain the seat tight relation whereby washer W is firmly clamped against rim 28 by the annular but flat shoulder 50 of head H.

According to the invention the upper enlarged portion of shell S is provided with the interrupted annular rim 40 from which lugs 16 extend. This rim forms a tight friction fit with walls of the annular channel 41 defined by the spaced annular ribs 42 and 43 integral with and within head H which also includes recess 44 for conveniently receiving the spaced lugs or ears 16 of the shell and also characterizes means for in part receiving the offset arms 14 of the pivoted closure 13. The friction fit between head H and shell S securely holds these parts together.

Various changes may be made in details of construction and arrangement of parts without departing from the spirit of the invention or sacrificing any of the advantages thereof inherent therein.

I claim:

1. A tank adapted to receive fuel from a nozzle, comprising; a shell including a cylindrical body having a plurality of vertically arranged and spaced bars and including a relatively large vertical relief opening, a head in part overhanging said body and secured to the upper part of said shell and having a centrally arranged horizontal orifice, a swingable arm connected to said shell and having a closure normally covering said orifice and adapted to be actuated by said nozzle for swinging thereof downwardly into said relief opening to preclude obstruction of the interior of said shell during discharge of fuel into the latter, and spring means cooperating with said arm to normally hold said closure within said orifice.

2. A tank cap adapted to receive fuel from a nozzle, comprising; a shell including a cylindrical body having a plurality of vertically arranged and spaced bars and including a relatively large vertical reentrant relief opening in communication with the bore of said shell, a head in part overhanging said body and secured to the upper part of said shell and having a centrally arranged horizontal orifice, a swingable arm connected to said shell and having a closure normally covering said orifice and adapted to be actu-

ated by said nozzle for swinging thereof downwardly into said relief opening to preclude obstruction of the interior of said shell during discharge of fuel into the latter, and spring means cooperating with said arm and head to normally hold said closure raised within said orifice.

3. A tank cap adapted to receive fuel from a nozzle, comprising; a shell including a cylindrical body having a plurality of vertically arranged and spaced bars and including a relatively large vertical relief opening and including a rim provided with spaced ears, a head in part overhanging said body and secured to the rim and having a centrally arranged horizontal orifice, fulcrum means carried by said ears, a swingable arm carried by said fulcrum means, a closure at one end of said arm and normally covering said orifice and adapted to be actuated by said nozzle for swinging thereof downwardly into said relief opening to preclude obstruction of the interior of said shell during discharge of fuel into the latter, and spring means in part surrounding said fulcrum means and cooperating with said arm and head to normally hold said closure within said orifice.

4. A tank cap adapted to receive fuel from a nozzle comprising a shell including a cylindrical body having a plurality of vertically arranged and spaced bars and including a relatively large vertical opening and including an upper rim provided with laterally extending spaced ears, a cylindrical head overhanging said body and having spaced ribs frictionally secured to said rim and having a recess for receiving said ears, said head having a centrally arranged horizontal orifice, fulcrum means carried by said ears, a swingable arm carried by said fulcrum means and severally receivable into said recess and in said opening, a closure integrally carried by and at one end of said arm and normally covering said orifice and adapted to be actuated by said nozzle for swinging thereof downwardly into said opening to preclude obstruction of the interior of said shell by said closure and arm during discharge of fuel into said shell, and spring means in part surrounding said fulcrum means and cooperating with said arm and head to normally hold said closure in covering relation to said orifice.

5. A tank cap adapted to receive fuel from a nozzle comprising; a shell including a cylindrical body having a plurality of vertically arranged and spaced bars and including a relatively large vertical opening and including an upper interrupted rim provided with laterally extending spaced ears, a cylindrical head overhanging said body and having spaced annular ribs frictionally secured to said rim and having a recess for receiving said ears, said head having a centrally arranged horizontal tapered orifice, fulcrum means carried by said ears, a swingable arm carried by said fulcrum means and severally receivable into said recess and in said opening, a tapered closure integrally carried by and at one end of said arm and normally covering said orifice and adapted to be actuated by said nozzle for swinging thereof downwardly into said opening to preclude obstruction of the interior of said shell by said closure and arm during discharge of fuel into said shell, and helicoidal spring means in part surrounding said fulcrum means and having terminals cooperating with said arm and head to normally hold said closure in covering relation to said orifice.

6. In combination, conduit means adapted to

receive fuel from a nozzle and having an inwardly overhanging seat including alined slots, a tank cap comprising a tubular shell embodying a vertically arranged relief opening in communication with the bore of said shell, a head fixed to the upper part of said shell and in part overhanging and surrounding the latter and including an orifice in communication with said bore, a swingable arm carried at the upper part of said shell, a closure at the inner end of said arm for normally covering said orifice and depressible into said opening to be clear of said bore, key means extending from said shell and receivable into said slot for positioning said cap on said seat, a washer mounted within said head and cooperating with said seat to provide a seal tight connection between said cap and conduit on rotation of said cap relative to said conduit, spring means carried by said key and cooperating with said seat to maintain said seal tight connection, and spring means for maintaining said closure and covering relation to said orifice.

7. In combination, conduit means adapted to receive fuel from a nozzle and having an inwardly overhanging annular seat including alined slots, a tank cap comprising a tubular shell embodying a vertically arranged relief opening in communication with the bore of said shell, a circular head fixed to the upper part of said shell and in part overhanging and surrounding the latter and including an orifice in

communication with said bore, a swingable arm carried at the upper part of said shell, a closure at the inner end of said arm for normally covering said orifice and depressible together with said arm into said opening to be completely out of said bore, key means extending from said shell and receivable into said slot for positioning said cap on said seat, a washer mounted within said head and cooperating with said seat to provide a seal tight connection between said cap and conduit on rotation of said cap relative to said conduit, leaf spring means carried by said key and cooperating with underface of said seat to maintain said seal tight connection, and spring means for maintaining said closure and covering relation to said orifice.
